SAFETY RAZOR BLADE SHARPENING
DEVICE

William A. Smith, Bronxville, N. Y.

Application June 1, 1942, Serial No. 445,528

2 Claims. (Cl. 51—211)

This invention relates to a unique safety razor blade sharpening device, particularly to those specializing in very thin blades, such as of the Gillette type.

An important feature of this invention, is the formation of a plurality of flat surfaces spaced at an obtuse angle to each other, so that when the thin blade is depressed and moved back and forth, the cutting or shaving edge or edges of the blade will contact the bevel or obtuse surfaces for the sharpening operation.

Another feature of this invention, is the adaptability of providing small or large sized devices, either of which may be for home use, the small size being preferable for the pocket or traveling bag or suit case.

Another feature of this invention, is the double sharpening device, in which the blade may be sharpened first on a roughened or abrasive surface, then finished on a smooth surface, both of which may be upper obtuse surfaces, or one on the upper and the other on the lower surfaces.

Other features of this invention will appear as the description proceeds in the following specification, accompanied by the annexed drawing, in which

Figure 1 is a perspective view of the large size sharpening device.

Figure 2 is a plan view of the same device.

Figure 3 is an end view of the same device.

Figure 4 is an enlarged fragmentary view of the base portion.

Figure 5 is an end view of a small size pocket device.

Figure 5a is a perspective view of the same small size pocket device.

Figure 6 is a similar view as Figure 5, disclosing a double device.

Figure 6a is a perspective view of the same double device.

Figure 7 is an end view of an alternative pocket size device.

Figure 8 is an enlarged sectional view of the blade showing one edge thereof being sharpened on the obtuse flat surface.

Figure 9 is a perspective view of a double device as shown.

Referring to the drawing, the numeral 10, a channel-like member, made of any suitable material, for example, of glass, porcelain, whet-stone or corundum, and the like. The device has a base portion 12 and flat surfaces 15 set on an obtuse angle to each other with a small curve portion 14 therebetween. These flat surfaces

start left and right of the intermediate horizontal surface 15a having adjacent extending flat surfaces 15b left and right therefrom at about 30 degrees, thence further flat surfaces 15c extending from first left and right flat surfaces at also about 30 degrees therefrom, or 60 degrees from the intermediate horizontal flat surface 15a, and may or may not have the vertical flat surfaces 15d as shown, this being optional.

10 It is to be noted in Figure 4, which is on an enlarged scale over Figure 3, that the thin razor blade B when moving over the flat surfaces enables the edges E to be guided to their obtuse sharpening surface 15 in a smooth-like manner, 15 the blade B being in a yielding position when straddling the curve portion 14, shown clearly in Figure 8, so edges E will continually become more tapering from the point, and not blunt-like, as the shoulder portion SH wears away, whereby the 20 sharpening operation provides a keen shaving edge. It is very essential that the obtuse angle be very precise for the sharpening of the edges E, this may vary around 150 degrees at A between the arch arrows in Figure 4, or the rise about 30 degrees more or less, depending on how thin or thick the razor blade B may be. The sectors S shown in Figure 3, may have their base SB, which are the flat surfaces 15, slightly less than the width of the blade B from edge E to edge E, so 25 that either one of the edges E will be constantly contacting the obtuse surfaces 15 in their movement back and forth by the finger F.

In Figures 1, 2 and 3, the device is shown about full size, such a large device is adaptable for home use, and to provide a small pocket size device, Figures 5, 5a; 6, 6a; 7, 7a; and 9, discloses such a device, similar in purpose, but alternatively different in design or formation of the obtuse surfaces, these similar parts having their same 35 numeral primed as indicated by 10', 10'', 10''' and 10''', either of which may be adopted.

In Figures 6, 6a, 7 and 9 a double device is shown having two sharpening surfaces each being of a different substance, one rough and the other smooth, for example, of abrasive material and hardened leather adapted to have applied thereon, corundum as desired, as indicated at 15' and 15'', 45 15a, 16 and 17, the rough surfaces 15a, 16 and 17 removing the burred edges, while the smooth surfaces 15' and 15'' finishes the sharpening 50 operation.

It is to be understood that blades that are not flexible may be sharpened on my device but the obtuse angle will then vary, that depending on 55

thickness of the blade and the draft of the shaving edges.

As shown in Figure 8, the edge 8 has about passed its sharpening operation onto the obtuse surface 15, it will be noted that in this view the point end will not become blunt-like, but will continue to be more thinner with the thin keen edge portion wearing away towards the shoulder SH at the full thickness of the blade B.

It is to be further understood that I may vary any part of my invention just so it comes within the scope of the appended claims.

Having thus described my invention, what I claim as new and desire to secure by Letters Patent of the United States of America is as follows:

1. In a flexible safety razor blade sharpening device of the character described, comprising a channel-like member having a base portion and side wall portions, said channel-like member having an intermediate flat surface on a horizontal plane and parallel to said base portion,

said horizontal flat surface having left and right flat surfaces extending therefrom at about 30 degrees, and further flat surfaces extending from said left and right flat surfaces at about 30 degrees therefrom and 60 degrees to said intermediate horizontal flat surface, all of said flat surfaces having a curved portion therebetween.

2. In a flexible safety razor blade sharpening device of the character described, comprising a channel-like member having a base portion, said base portion provided with an intermediate horizontal flat surface having left and right flat surfaces extending at about 30 degrees therefrom, further flat surfaces extending from said left and right flat surfaces at about 30 degrees and 60 degrees to said horizontal flat surface, said further flat surfaces terminating into vertical flat surfaces extending at about 30 degrees therefrom, all of said flat surfaces having a curved portion therebetween.

WILLIAM A. SMITH.
